DESIGN FOR A TABLE RADIO CABINET

Arthur C. Heise and Millard W. Jacobi,
Baltimore, Md.

Application September 19, 1936, Serial No. 64,932

Term of patent 3½ years

To all whom it may concern:

Be it known that we, Arthur C. Heise and Millard W. Jacobi, both citizens of the United States, residing at Baltimore, Maryland, have invented a new, original, and ornamental Design for a Table Radio Cabinet, of which the following is a specification, reference being had to the accompanying drawing forming a part thereof.

Fig. 1 is a perspective view of a table radio cabinet embodying our new design;

Fig. 2 is a front elevation thereof; and
Fig. 3 is an end elevation thereof.

We claim:

The ornamental design for a table radio cabinet, as shown.

ARTHUR C. HEISE,
MILLARD W. JACOBI.
